UNITED STATES PATENT OFFICE.

WILLIAM A. CLAY, OF ROCHESTER, NEW YORK.

FOLDING CHAIR.

1,118,530.

Specification of Letters Patent. Patented Nov. 24, 1914.

Application filed May 31, 1913. Serial No. 770,854.

To all whom it may concern:

Be it known that I, WILLIAM A. CLAY, of Rochester, in the county of Monroe and State of New York, have invented a new and useful Improvement in Folding Chairs, which improvement is fully set forth in the following specification and shown in the accompanying drawings.

The present invention relates to folding chairs, seats or stools and an object of the same is to provide a structure which is inexpensive to manufacture and is strong and durable in use, and which may be folded into small compass to permit it to be readily carried or stored.

To these and other ends the invention consists in certain parts and combinations of parts all of which will be hereinafter described, the novel features being pointed out in the appended claims.

In the drawings: Figure 1 is a perspective view of the chair or stool folded; Fig. 2 is a side view of the device ready for use; Fig. 3 is a sectional view through the same when folded; Fig. 4 is a vertical section through the device when ready for use; Fig. 5 is a front view of the chair; Fig. 6 is a section through the chair at right angles to that shown in Fig. 4, the back being lowered; and Figs. 7 and 8 are detail views showing the connection of the braces with the legs.

In the illustrated embodiment of the invention, there is provided a seat portion preferably comprising a rectangular frame 1 having the upper surface thereof countersunk to receive a bottom 2 made of papier-mâché, leather or similar thin material.

The supporting means for the seat preferably embodies two supports. One of these supports comprises two legs 3 connected by a cross piece 4 and pivoted at their upper ends at 5 to the inner faces of opposite sides of the rectangular frame so that they may be folded to be housed within said frame, the length of the said legs being just sufficient to be received within the frame. The other support also embodies two legs or standards 3^a connected by a cross piece 4^a, the distance between the legs 3^a being less than the distance between the legs 3, and said legs 3^a, instead of being pivoted to the sides of the frame 1, being pivoted to the ends of a block 6 which is secured to one of the sides of and

within the rectangular frame 1. The legs 3^a are also formed near their lower ends with recesses 7. This arrangement permits both supports to be folded within the rectangular frame 1 so as to be entirely protected by the latter. The legs 3 lie on the outer sides of the legs 3^a and the cross piece 4 is received within the notches 7. Of course, the legs 3^a must be folded within the frame before the legs 3 for otherwise the legs 3^a would engage the cross piece 4.

Suitable means may be provided for bracing the legs in their open positions. In the present instance, the legs 3 are provided with vertical or longitudinal grooves or ways 8 extending from a point near the outer ends of said legs and preferably having notches 9 at the ends thereof and also pockets or openings 10. Operating in each groove or way 8 is a laterally-turned portion or projection 11 on the end of the brace 12. The two braces 12 are connected by a portion 13 mounted to turn on the seat in a manner to be described and forming with the braces 12 a U-shaped member. The legs 3^a may also be formed with longitudinal ways or grooves 8^a in which work laterally-turned portions 11^a on braces 12^a, the latter being connected at their other ends by a portion 13^a pivoted in a manner to be described. It will be noted that the guide 8^a does not have any notches or recesses at its end but it is provided at its upper part with a pocket 10^a in which the projection 11^a enters to hold the legs open.

In order to provide a firm support for the brace members, a sheet metal plate 14 is extended across or bridges the rectangular frame and has its opposite edges rolled at 15 to provide bearing sleeves for the horizontal portions of the U-shaped brace members.

To fold the legs or supports of the chair, the braces 12^a are moved laterally at their lower ends to remove them from the pockets 10^a, after which the support having legs 3^a may be swung inwardly to the position shown in Figs. 1 and 3, the lower end of the braces 12^a moving toward the lower ends of the slots 8^a. The other support which has the legs 3 can then be folded inwardly by flexing the braces 12 to remove their ends 11 from the pockets 10 and the upper notches 9, after which the ends 11 would travel in the

ways or grooves 8 until the support is folded and the ends of the braces enter the lower notches 9 and lower pockets 10. These lower notches 9 are provided in order that the 5 braces 12 will lie flush with those faces of the legs 3 which are opposed to the legs 3^a and, in this way, the legs 3^a and 3 may lie close or in contact with each other, thus giving a compact arrangement. The upper 10 notches 9 also permit the braces 9 to lie flush with legs 3 so that such braces will not interfere with the swinging of the other support.

The chair may be provided with a back which may embody a U-shaped member 16 formed of wire or a rod and having the 15 free ends of its arms turned inwardly and pivoted to the outside faces of the rectangular frame 1 substantially midway between the upper and lower edges of said 20 frame. This arrangement permits the back frame to swing so that its arms hug the sides of the chair seat and its horizontal connecting portion lies in proximity to the front wall of the seat. The back frame may 25 be provided with a looped or bent portion 18 to form a handle for carrying the chair or stool. The sides of the back frame may be connected by a rest or cross piece 19 which may be ornamentally shaped and may 30 be mounted to slide on the side arms of the back frame for the purpose to be described. Preferably this rest or cross piece is formed from sheet metal and has forwardly offset flanges 20 at its vertical edges, said flanges 35 being formed with grooves 21 for receiving the side arms of the back frame. This arrangement prevents the rest or cross piece interfering with the folding of the back because the main portion of the rest or cross 40 piece is in a plane in rear of the back frame, the flanges, when the back frame is lowered, lying on opposite sides of the rectangular bottom frame as will be seen by referring to Fig. 6, while the rest or cross piece 19 lies close to the upper surface of the bottom 45 and will permit the chair to be used as a stool without a back as shown in this figure.

To support the back in its upright position, braces 22 may be provided, the latter 50 being pivoted at their lower ends at 23 to the outer faces of the rectangular frame below the pivots of the back frame. The upper ends of the braces are pivoted at 24 to lips 25 extending from the flanges 20. With 55 this arrangement, the swinging of the back frame toward or from its upright position causes the back rest 19 to slide on the upright arms of the back frame, this being due to the fact that the braces 12 are connected 60 to the back piece 19. Straps 26 hold the rest or cross piece to the back frame.

A chair or stool constructed in accordance with this invention is especially designed for use in places where space has to be taken into consideration, such, for instance,

as in automobiles, and camps and for viewing parades, the stool or chair being easily carried. The supporting means or legs are very strong and are braced in such a manner that they may be readily folded into 70 compact form. The back is so constructed that it does not add materially to the weight of the chair nor does it take up very much space when folded. It serves as a handle for carrying the chair and it does not interfere with the use of the chair as a stool. 75

What I claim as my invention and desire to secure by Letters Patent is:

1. The combination with a rectangular frame, and a sheet of material covering the upper side of said frame, of a strip of sheet metal bridging said frame and having its opposite edges rolled to provide bearings, a pair of supports hinged to the frame to swing inwardly within said frame, each of 85 said supports having a pair of legs provided with longitudinal grooves, and a pair of U-shaped brace members each of which has a horizontal portion turning one of the rolled 90 bearings and also has a pair of arms with laterally turned ends operating in the grooves of the legs.

2. The combination with a rectangular frame and a sheet of material closing one side of the frame, of a strip of sheet metal bridging the frame and having opposite edges rolled to provide bearings, a pair of supports pivoted to the frame and each embodying two legs formed with longitudinal 95 grooves, the legs of one support being received between the legs of the other support, and the legs of the outer support having recesses at the lower ends of their 100 grooves, and a pair of brace members each embodying a horizontal portion turning in 105 one of the rolled portions and arms having laterally-turned ends working in the grooves of the legs, the arms coöperating with the outer legs being received within the recesses when the legs are folded within the rectangular frame.

3. In a folding chair, the combination with a bottom frame, of a back frame pivotally mounted thereon, a cross piece connecting the sides of the back frame and 115 guided on the latter, and braces pivoted to the bottom frame and to the cross piece.

4. In a folding chair, the combination with a bottom frame, of a back frame formed from a U-shaped member having its arms pivoted to the sides of the bottom frame, a cross piece made from sheet metal and having forwardly-extending flanges at opposite sides thereof guided on the arms of the back frame, and braces pivotally connected to the bottom frame and to the cross 120 piece.

5. In a folding chair, the combination with a bottom frame, of a U-shaped back frame formed from a rod and having its 130

arms pivoted to the bottom frame, said back frame being adapted to fit about the bottom frame when folded toward the latter, a cross piece formed from sheet metal and 5 having forwardly extending flanges at its opposite edges grooved to receive the arms of the back frame, and braces pivotally con-

nected to the bottom frame and to the cross piece.
